UNITED STATES PATENT OFFICE.

NEIL D. SWEET AND THOMAS A. SWEET, OF COLON, MICHIGAN.

SOLE-STITCHING MACHINE.

Application filed March 14, 1922. Serial No. 543,667.

To all whom it may concern:

Be it known that we, NEIL D. SWEET and THOMAS A. SWEET, citizens of the United States, residing at Colon, county of St. Joseph, State of Michigan, have invented certain new and useful Improvements in Sole-Stitching Machines, of which the following is a specification.

This invention relates to improvements in sole stitching machines.

Our improvements relate particularly to sole stitching machines for use in repairing shoes and we have illustrated the same as embodied in a machine designed for that purpose, although certain features are adaptable for use in other machines, that is, machines designed for use in manufacturing shoes.

The main objects of the invention are:

20 First, to provide an improved sewing machine for use in attaching or stitching soles to shoes in repair work which is simple in structure and very easy to operate.

Second, to provide in a machine of the class described an improved means for waxing the thread.

Further objects, and objects relating to structural details, will definitely appear from the detailed description to follow.

30 We accomplish the objects of our invention by the devices and means described in the following specification. The invention is clearly defined and pointed out in the claims.

35 A structure which is a preferred embodiment of our invention is clearly illustrated in the accompanying drawing, forming a part of this application, in which:

Fig. I is a side elevation of a machine embodying our improvements, a shoe being shown in position to be operated upon by the dotted lines, the bench being partially broken away.

Fig. II is a detail rear elevation.

45 Fig. III is a detail side elevation showing the arrangement of the parts upon the bench.

Fig. IV is an enlarged detail of the left hand side of the machine.

50 Fig. V is a side elevation of one of the thread waxing receptacles partially broken away to show structural details.

Fig. VI is a detail view partially in vertical section on a line corresponding to line 6—6 of Fig. V.

55 Fig. VII is a detail section on a line cor-

responding to line 7—7 of Figs. I, IV and IX, showing details of the shuttle.

Fig. VIII is a detail section on a line corresponding to line 8—8 of Fig. VII, showing further details of the shuttle.

Fig. IX is a front elevation of the shuttle box supporting spring.

In the drawing similar reference characters refer to similar parts throughout the several views and the sectional views are taken looking in the direction of the little arrows at the ends of the section lines.

Referring to the drawing, the bench 1 is provided with suitable legs 2 adapted to support the mechanism in convenient position for the operator. A main supporting upright 3 is mounted upon the bench. The frame 4 of the machine is secured to this upright.

At the upper end of the upright is a driving wheel 5 connected to the power wheel 6 by the belt 7 and pulley 8. The pulley 8 is controlled by the clutch 9 operatively connected to the foot lever 10 by the link 11. The details of these parts are not further illustrated as they form no part of our present invention.

The frame 4 is provided with a work rest 12 on which the work, as 13, is supported by the operator, the work rest being in the form of spaced projections on the frame of such dimensions as to receive the edge of the sole. The presser foot 14 is controlled by a mechanism, indicated generally by the numeral 15, so that it is manually raised and lowered,—see Fig. IV. As the details of this presser foot control mechanism form no part of this invention they are not further illustrated or described herein.

The needle bar 16 is driven from the rocker 17 which is in turn operated from the slide 18 reciprocating in the vertical slot 19 and provided with a roller, shown by the dotted lines 20, engaging the slot 21 in the rocker. The slide 18 is connected by the pitman 22 to the driving wheel 5, so that as the wheel rotates the needle bar is reciprocated.

The shuttle 23 is arranged in a shuttle box 24 and carries the bobbin 25. The shuttle is supported by a spring 26 formed integrally with the disk 27 from which it is struck in the form of a tongue, the spring being bowed outwardly with its end lying in the slot 28, so that it is not likely

to be engaged by the thread as it is looped by the shuttle, the thread passing between the spring and the spherical head 29 of the shuttle against which the spring bears as 5 the loops are formed.

The spring has a peripheral notch or cut-away portion 30 to pass the shuttle driving lug 31,—see Fig. VIII. The details of the shuttle mechanism are not illustrated as 10 they form no part of this invention. This supports the shuttle in upright position so that the shuttle always catches the loops of the top thread formed by the needle with the parts in this upright position.

15 The feed lever 32 is provided with a point 33 adapted to engage the sole as it is supported upon the rest 12, the feed lever being oscillated by a suitable mechanism, not illustrated. The stop screw 34 limits the 20 return movement of the feed lever and, thus limiting its stroke, determines the length of the stitch.

To automatically wax the thread 35 as it passes to the needle, we provide a receptacle 36 through which the thread is carried as it passes from the spool 37 to the take-up mechanism, designated generally by the numeral 38. This receptacle is provided with a guide member 39 having an eye 40 at its 25 lower end through which the thread is passed as it is unwound from the spool, the thread being then passed through the eye 41 at the top of the guide member and from thence through a hole 42 in the closure or 30 plug 43 for the receptacle 36. This closure carries a thread guide 44 of U-shape having eyes 45 and 46 formed therein, the eye 45 being at the lower end of the guide and below the level of the wax so that the thread 35 is carried down into the wax and in passing 35 through this eye the fibres of the thread are spread or opened so that the wax effectively penetrates and thoroughly waxes the thread. The eye 46 is above the level 40 of the wax so that it serves as a wiper wiping off the excess from the surface of the thread. The thread passes from the eye 46 through the closure plug to the take-up 45 mechanism, as described. The plug or 50 closure is retained in the receptacle by the pin 47, there being considerable strain or pull on the thread as it is drawn through the receptacle.

To give tension to the thread a tension 55 spring 48 is provided which is adjustably mounted on the frame with its free end bearing against the thread on the spool. The adjusting screw 49 is provided to regulate the tension of this spring and through it the 60 tension of the thread.

A similar wax receptacle, designated by the numeral 50, is mounted on the bench so that as the thread is wound upon the bobbin 25 the thread may be passed through the

waxing receptacle. To continuously wind 65 the thread and pass it through the wax receptacle we utilize a winding spindle 51 having a crank 52, the same being mounted in a convenient position on the upright 3.

We are familiar with machines on the 70 market designed for repair work, but these are usually designed to be operated by hand, the frame of the machine being placed in a horizontal position and the operator making the stitches by manually reciprocating 75 the parts corresponding to the slide 18. This is laborious work and very rapid work is not possible. It is also necessary to hold the work in an unnatural and inconvenient position and in a position in which it is 80 quite difficult for the operator to properly inspect the work.

Our improved machine enables very rapid work and work of high quality and also with a minimum of labor on the part of the 85 operator.

We have illustrated and described our 90 improvements in an embodiment which we have found very satisfactory. We have not attempted to illustrate or describe certain 95 modifications and adaptations which might be desirable in general manufacture, as we believe the disclosure made will enable those skilled in the art to which this invention relates to embody or adapt the same as may 95 be desired.

Having thus described our invention, what we claim as new and desire to secure by Letters Patent, is:

1. In a structure of the class described, 100 the combination with a supporting upright, a driving wheel mounted at the top thereof, a sewing machine comprising a frame, work rest, presser foot, needle-bar, shuttle, said frame being mounted on said upright below 105 said driving wheel, and means for operating said needle-bar comprising a rocker member operatively associated therewith, a slide vertically reciprocating on said frame, a pitman connecting said slide to said driving 110 wheel, and a roller on said slide, said rocker member being slotted to coact with 115 said roller.

2. In a structure of the class described, 120 the combination with a supporting upright, 115 a driving wheel mounted at the top thereof, a sewing machine comprising a frame, work rest, presser foot, needle-bar, shuttle, said frame being mounted on said upright below 125 said driving wheel, and means for operating said needle-bar comprising a slide vertically reciprocating on said frame and operatively 130 associated with said needlebar.

In witness whereof, we have hereunto set our hands and seals.

NEIL D. SWEET. [L. S.]
THOMAS A. SWEET. [L. S.]
